UNITED STATES PATENT OFFICE.

THOMAS F. O'CONNELL, OF CHICAGO, ILLINOIS, ASSIGNOR TO PARAMOUNT HOSIERY FORM DRYING CO., OF CHICAGO, ILLINOIS, A CORPORATION OF ILLINOIS.

DRYING AND SHAPING STRUCTURE FOR DRYING LACE HOSIERY.

1,402,532.

Specification of Letters Patent.

Patented Jan. 3, 1922.

Application filed May 27, 1919. Serial No. 300,137.

To all whom it may concern:

Be it known that I, THOMAS F. O'CONNELL, a citizen of the United States of America, residing at Chicago, in the county of

5 Cook and State of Illinois, have invented certain new and useful Improvements in Drying and Shaping Structures for Drying Lace Hosiery, of which the following is a specification, reference being had therein

10 to the accompanying drawing.

This invention relates to hosiery drying and shaping structures, and has especial reference to a drying form or "board" adapted for treating so-called lace or 15 French stockings, that is, hosiery or a stocking, which adjacent the ankle-portion thereof, is composed of a lace-formation, or of a drop-stitch construction.

The object of the invention is, primarily, 20 to provide a device of the kind specified that is adapted to apply heat to the internal surface of the fabric of the article and also to effect a shaping of the same by means made effective on such internal surface; the 25 desideration being to dry and simultaneously shape the hosiery in a single operation and by a single instrumentality, the shaping involving the creasing of the hosiery along oppositely disposed lines, and a simultaneous flattening and smoothing of the 30 article intermediate the creases, so that it will lie approximately flat when the drying and shaping operations are completed.

A more specific object of the invention is 35 simultaneously to dry and finish hosiery suitable for the market; in other words, by utilizing a particular mode of procedure and by using the instrumentality constituting my invention, the hosiery will be creased at 40 its sides, flattened, ironed and smoothed at the front and rear portions, the heel shaped and formed, etc., and have an ironed and finished appearance, such that no subsequent operations, other than marking, banding and 45 packaging the same, are required.

A still further object within the contemplation of my invention is to provide a suitable device for drying and shaping so-called lace or drop-stitch hosiery, such that 50 the creases will be at the sides—in contradistinction to the position of such creases in the more usual types of seamless and full-fashioned hosiery—and in which the foot portion, instead of being angulated in relation to the leg portion of the article, lies

flat, but with the heel section properly formed and preferably outstanding from the plane of the surface of the rear side of the stocking.

Still another object of the invention is to 60 provide a structure in which the seam of a full-fashioned stocking is or may be precisely lined up centrally of the article and in a substantially straight line from the toe, along the heel, and through out the leg portion. 65

With these and other objects in view, the invention resides in the structure, in the shaping-sections thereof, and in the arrangement therein for heating the same 70 whereby it may impart its heat to the stocking and thereby effect rapid evaporation of all water or moisture therein and, at the same time, to finish the article completely and ready for the trade. 75

In order that the invention may more readily be understood, I have illustrated a preferred form of the structure in the accompanying drawings; these being merely 80 illustrative of an embodiment of my inventive concept; it being understood that the structure is susceptible of considerable variation and modification without departing from the spirit of the invention and without sacrificing any of the underlying 85 principles and salient features thereof.

In these drawings:

Figure 1 is a view in front elevation of the form, with the heel-shaping portion shown as outstanding therefrom; 90

Figure 2 is a similar view of the opposite side of the structure;

Figure 3 is a view in edge elevation of the improved hosiery drying and shaping form;

Figure 4 is a fragmentary view on an 95 enlarged scale in longitudinal vertical section on the line 4—4, Fig. 2;

Figure 5 is a similar view on the line 5—5, Fig. 2;

Figure 6 is also a fragmentary view on an 100 enlarged scale partly in section, similar to Fig. 5 and showing a portion of a stocking thereon with the seam of the stocking being shown in its operative position in the seam-receiving groove formed on the heel-side 105 of the device;

Figure 7 is a view in perspective of the drying and shaping form with a stocking disposed thereon, portions of the latter being broken away to show the relative posi- 110

tions of its parts in respect to the effective portions of the drying and shaping form;

Figure 8 is a fragmentary view in perspective of a modified form of structure in which the heel shaping section thereof extends longitudinally of the form instead of transversely thereof as in the preferred type of structure; and

Figure 9 is also a fragmentary view in elevation, partly in section, of another modification in which the form is solid instead of hollow.

As is well known in the art, there are two general types of hosiery now manufactured; one of these being the so-called "seamless" type of hosiery (which is knit in tubular form) and the other is the so-called full-fashioned (which is knit in a flat shape and "fashioned", then sewed to form a seam at the rear). It is the practice, nowadays, to knit or produce these two types of hosiery with more or less fancy or artistic formations at the front of the article adjacent the ankle-portion thereof. These formations comprise either a drop-stitch construction, lace work, or figured imprints. In order that these ornate formations may be more effectively and conveniently displayed, as when the hosiery is boxed, as well as when disposed for exhibition in show windows and the like, the practice has developed of presenting the fancy portion of the hosiery at the front and to dispose the heel more or less out of sight. To this end, the front and rear portions of the article are so treated as to lie flat, with crease-formations at the junction of the so-called front and rear portions. The heel, which is formed when the article is being knit, stands out more less from the body portion of the article.

It is to be understood that my invention has utility in connection with both of the aforementioned types of hosiery. In so far as it involves the simultaneous drying and shaping of moist, that is, wet hosiery by subjecting the internal surface of certain portions of such hosiery to a flattening, smoothing or ironing action, simultaneously with the effecting of crease-like formations at other portions whereby the article will be caused to assume a flattened shape, and during which treatment of the hosiery the fabric thereof is simultaneously dried and set by the application of heat to the internal surface of the same so that the article will retain its flattened shape, my invention utilizes the principles of the method disclosed in U. S. Patent No. 1,204,945, granted Nov. 14, 1916, on the invention of George Collis. In so far as the device includes a metal drying and shaping form, relatively thin in cross section, and hollow to contain a heating medium, and having portions of its sides beveled to produce relatively reduced edges 65 and being curved intermediate of such edges

to provide oppositely disposed fabric shaping surfaces, my invention somewhat resembles but is inventively distinguishable from the structure of U. S. Patent No. 1,207,496, granted December 5, 1916, on the invention of Walter D. Butz. Inasmuch, however, as the invention contemplates the drying of a hosiery article in such manner that the creases shall be formed in the sides of the article, instead of at the front and rear portions thereof, and since the foot portion is not angulated, in forming the stocking while drying, and as the heel section of the article is to be formed so as to be folded down against the body portion of the hosiery, the present invention is differentiated from the devices disclosed in the patents aforementioned, and includes features for producing novel results not contemplated in those patents. Besides, the device of the present invention may, if desired, be used in conjunction with the practice of applying heat externally to the article. Hence, it is to be understood that the present invention is not limited to the precise type and construction of hosiery drying and shaping forms herein disclosed; and, as exemplifying variations from this type, I have shown modifications thereof in Figs. 8 and 9.

Referring to these drawings and to Figs. 1 to 7 thereof, the reference-numeral 1 designates, generally, a hosiery drying and shaping form which includes a foot portion 2, a heel section 3, a leg portion 4, and a base portion 5.

This is my preferred type of construction, and contemplates the provision of a channel or similar conduit 6 for the passage of steam or other thermal medium therethrough in order to heat the form and, thus, cause it to impart a drying heat to the hosiery after the latter has been stretched on the form. The channel 6 extends from the base portion to the toe 7 of the form, and is divided by a partition 6^a (Fig. 1) and the two openings 8 at opposite sides of this partition in the base portion communicate with apertures 9 in a steam-supplying pipe 10 that is connected with a suitable source of steam supply.

In this instance, the foot portion is formed in alinement with the leg portion, preferably and as shown.

To effect crease formations in the hosiery which is boarded on the form, the latter is provided with two oppositely disposed, reduced, crease-producing edges 11 and, likewise, the toe section 7 of the foot portion 2 is provided with a crease-forming edge 12.

The sides 13 and 14 of the device between the crease-producing edges, are (preferably and as shown) curved to present arc-shaped surfaces (13^a and 14^a, Fig. 7) adapted to effect a flattening and smoothing action of the fabric of the hosiery when in contact there-

with. The arc-shaped, fabric-flattening surfaces preferably extend throughout the entire length of the hosiery shaping form and down to the base portion, as shown; and it follows from this that the foot portion 2 has the curved, arc-shaped surfaces also.

To form the heel section of the hosiery and, thus, to shape it properly, it is desirable, though not absolutely essential, to provide a heel forming surface on the device; and, to this end, I have, in the embodiment of Figs. 1 to 7, shown a heel forming protuberance or extension 15, this outstanding from the form and preferably including a crease-forming or fold-producing edge 16, this edge preferably extending transversely of the form and adapted to effect a crease or fold 17 in the heel of the hosiery.

Where full-fashioned hosiery is to be "boarded" on the form, it is desirable that means be provided for lining up the seam thereof; and to this end the heel side 14 of the form is provided with a groove 18, preferably beginning adjacent the toe 7 and extending up over the heel-forming section 15, and along the leg portion 4; this groove preferably being disposed centrally so that the seam of the hosiery may be "centered" and thus, properly disposed with reference to the creases in its sides.

In Figure 8, I have shown a somewhat modified type of form 19; the modification, in this instance, involving a different arrangement of the heel section 20: Therein, the heel section extends longitudinally of the form, instead of transversely as in the previously described type. This form of heel section may be preferred by some manufacturers, where it is desired to have the heel of the hosiery folded longitudinally down against one side, rather than to have the point thereof disposed centrally of the article, as in the arrangement of Fig. 6.

In Figure 9, I have shown a still different modification; this involving a solid form 22, made of metal, wood, or other appropriate material, having a heel forming section 23 and otherwise of the general construction and formation of the hosiery drying and shaping form illustrated in Figs. 1 to 7.

Operation: In practicing the so-called "paramount method"—disclosed in and covered by the aforementioned patent No. 1,204,945—with the type of forms herein shown in Figs. 1 to 8, the hosiery—which is more or less wet when received from the dyeing, bleaching or mercerizing bath of the dye house in the mill, and consequently requires drying and finishing—is stretched by the "boarder" upon the form so that the top 24 of the hosiery may be pulled down as near as possible to the base 5 of the form. The heat of the form is such as immediately to start the evaporation of the moisture in the hosiery, and as this evaporation continues,

the fabric is set so that it will become fixed and retain the shape in which it is formed by the device. The shaping is effected simultaneously with the drying and setting of the fabric, and such shaping is accomplished by the curved sides 13 and 14 of the form—which effect a flattening and smoothing action—while the crease-forming edges 11 produce crease formations in the sides of the hosiery, that is in the leg and foot portions thereof. After the stocking has been on the form for from 3 or 4 to 10 or 15 minutes—according to the weight of the yarn in the hosiery—the same will have been simultaneously dried and finished; whereupon the operator strips the hosiery article from the form. It is then ready for pairing, marking and packaging.

From the foregoing, it will be perceived that I have devised a simple but effective instrumentality for drying and simultaneously shaping hosiery of the lace or drop-stitch type wherein the creases are formed at the sides, rather than at the front and rear, and wherein the heel is formed to outstanding from the body of the fabric and then be folded or laid down in any desired way.

By reason of the characteristics set forth in the aforementioned Patent No. 1,207,496, I prefer to make the form of aluminum, or of a material which includes aluminum.

Since there is a tendency of the fabric to creep up on the form while drying and before the fabric sets, I find it desirable to provide means for preventing such a creeping tendency; and, to this end, fabric-holding devices 25 are disposed on opposite sides of the form, as shown, for example, in Figs. 1, 2, and 3.

What I claim is:

1. A hosiery drying and shaping form relatively thin in cross-section and having arc-shaped, fabric-flattening front and rear faces, the width dimensions of which vary intermediate the ends of the form, and having, also, oppositely-disposed crease-producing side edges, and including an elongated leg-portion, a foot-portion extending in longitudinal alinement therewith, and an integral heel-section between the leg and foot-portions and outstanding from the rear face thereof at the lower end of and as a continuation of the foot-portion.

2. A hosiery drying and shaping form including an elongated leg-portion, a foot-portion extending in longitudinal alinement therewith, and an integral heel-section outstanding from and formed as a continuation of the foot-portion; the form being hollow to contain a heating medium and having its front and rear faces arc-shaped, and having crease-producing edges, the heel-section extending from the rear face and also hollow.

3. A hosiery drying and shaping form in-

- cluding an elongated leg-portion, a foot-portion extending in longitudinal alinement therewith, and a heel-section outstanding from both the leg and foot-portions, both the leg and foot-portions and the heel-section being hollow to contain a heating medium; the heel-section extending in a direction at a substantial angle to the edges of the form.
- 10 4. A hosiery drying and shaping form relatively thin in cross-section and having arc-shaped fabric-flattening front and rear faces and oppositely-disposed crease-producing edges and including an elongated leg-portion, a foot-portion extending in longitudinal alinement therewith, and a heel-section outstanding from the rear face of the form between the leg and foot-portions and formed as a continuation of the foot-portion; the leg and foot-portions and the heel-section being hollow to contain a heating medium; the heel-section being formed on the rear face intermediate the crease-producing edges.
- 15 5. A hosiery drying and shaping form relatively thin in cross-section and having arc-shaped fabric-flattening front and rear faces and oppositely-disposed crease-producing edges and including an elongated leg-portion, a foot-portion extending in longitudinal alinement therewith, and a heel-section outstanding from the rear face of the form between the leg and foot-portions and formed as a continuation of the foot-portion; the leg and foot-portions and the heel-section being hollow to contain a heating medium; the heel-section being formed on the rear face intermediate the crease-producing edges and having, itself, a fold-forming edge.
- 20 6. A hosiery drying and shaping form including a leg-portion having arc-shaped front and rear faces which terminate in two oppositely-disposed crease-producing edges; a foot-portion having arc-shaped fabric-flattening front and rear surfaces which terminate in crease-producing edges; and an integral heel-section outstanding from the leg and foot-portions and having a fold-forming edge lying in a plane between the crease-producing edges of the leg and foot-portions; the leg and foot-portions and the heel-section being hollow to contain a heating medium.
- 25 7. A hosiery drying and shaping form, 55 hollow to contain a heating medium and having a partition to form an internal channel in the form; the latter having arc-shaped front and rear faces which terminate in two oppositely-disposed crease-producing edges that extend in opposite directions from that of the partition; the form including an elongated leg-portion, a foot-portion extending in longitudinal alinement therewith and an integral heel-section outstanding from the leg and foot-portions and having, itself, a fabric-folding edge that lies between the crease-producing edges of the form.
- 30 8. A hosiery drying and shaping form 70 having arc-shaped front and rear faces which terminate in oppositely-disposed crease-producing edges and including an elongated leg-portion, a foot-portion extending in longitudinal alinement therewith, 75 and a heel-section outstanding from the leg and foot-portions and having a fabric-folding edge formed thereon between the crease-producing edges of the leg and foot-portions; the form being hollow and channeled internally to contain a heating medium, and having a seam-receiving groove extending centrally of the form along the leg and foot-portions and centrally of the heel-section.
- 35 9. A hosiery drying and shaping form in- 85 cluding an elongated leg-portion; a foot-portion extending in longitudinal alinement therewith; and an integral heel-section between the foot and leg-portions and outstanding substantially beyond the plane 90 thereof; the leg and foot-portions each having two oppositely-disposed arc-shaped fabric flattening surfaces and two oppositely-disposed crease-producing edges, and the heel-section having a crease-producing edge ex- 95 tending transversely of the form and at an angle to the crease-producing edges of the foot and leg portions; one of the fabric-flattening surfaces being provided with an elongated seam-receiving groove, said groove cutting through the crease-producing edge of the heel-section.
- 40 In testimony whereof I affix my signature in presence of two witnesses.
